UNITED STATES PATENT OFFICE.

PAUL HOFFMAN, OF WESTERN SPRINGS, ILLINOIS.

RAILROAD FROG.

Application filed May 19, 1924. Serial No. 714,276.

To all whom it may concern:

Be it known that I, PAUL HOFFMAN, a citizen of the United States, and resident of Western Springs, in the county of Cook 5 and State of Illinois, have invented a certain new and useful Improvement in Railroad Frogs, of which the following is a full, clear, concise, and exact description, reference being had to the accompanying drawings, forming a part of this specification.

This invention relates to railroad frogs, and particularly to the type of railroad frog which has a removable portion at the section where the wheel flangeways cross.

15 The wheel supporting portions of a railroad frog are worn very rapidly at the point of the frog and at the rail sections on each side of the point. This is due to the fact that when a wheel is passing over the frog, 20 a portion of the tread surface of the wheel lies over the flangeway and thus the load carried by the wheel is supported on a rail surface of less width than the wheel supporting surface of the normal rail. As a 25 consequence, the point of the frog wears away very rapidly, and the adjacent rail portions also are cut away due to the edge of the wheel engaging and rolling onto the side of the rail adjacent to the frog point.

30 The expedient of providing a frog center of hard wear-resisting metal, as manganese steel, has been employed, but notwithstanding the use of the manganese steel, the point of the frog and adjacent rail portions are 35 still found to wear away very rapidly, thus necessitating the replacement of the frog center.

The object of the present invention is to provide in a railroad frog removable and 40 replaceable sections at the point of the frog and adjacent wear rail sections on opposite sides of the frog point, thus permitting the worn section of the frog, whether the point or rail portion on either side thereof, to be 45 removed and replaced by a similar portion without the renewal of the entire frog or frog center.

It is believed the invention will be understood most readily from a detailed description thereof taken in connection with the accompanying drawings, in which—

Figure 1 is a plan view of the frog of the present invention;

55 Figure 2 is a section on the line 2—2 of Figure 1;

Figure 3 is a section on the line 3—3 of Figure 1;

Figure 4 is a section on the line 4—4 of Figure 1;

Figure 5 is a section on the line 5—5 of 60 Figure 1;

Figure 6 is a section on the line 6—6 of Figures 1 and 11.

Figure 7 is a section on the line 7—7 of Figure 1;

Figure 8 is a section on the line 8—8 of 65 Figure 1;

Figure 9 is a vertical central section through the frog substantially on the line 9—9 of Figures 2, 3, 4, 5 and 6, but showing the removable point section in side elevation.

Figure 10 is a section substantially on the line 10—10 of Figure 11;

Figure 11 is a section substantially on the 75 line 11—11 of Figure 4;

Figure 12 is a plan view similar to Figure 1, of a modified form of applicant's invention;

Figure 13 is a section substantially on the 80 line 13—13 of Figure 12;

Figure 14 is a section substantially on the line 14—14 of Figure 12;

Figure 15 is a section on the line 15—15 of Figure 12;

Figure 16 is a section on the line 16—16 of Figure 12; and

Figure 17 is a section on the line 17—17 of Figure 15.

Referring now to the drawings, in which like reference characters indicate the same parts in the several views, 10 indicates one of the rails and 11 a continuation of the rail 10 on the opposite side of the flangeway crossing. Integral with the rail 11 is the 95 wing rail portion 12. At 13 is indicated another rail having the continuation 14, integral with which is the rail wing portion 15. The frog here shown is of the type having a central portion of hard metal, as manganese steel, the manganese steel portion being clamped between the extensions 12 and 15 of the rails 11 and 14. A frog of this type is commonly known as the rail bound frog.

The manganese center of the frog 105 comprises the one piece body exposed from above in the portion 16 clamped between the rails 10 and 13, the tapering central portion 17 which terminates in the removable

or replaceable point portion 18, the rail 110

wear portions 10 and 20 integral with the central portion, the replaceable rail wear portions 21 and 22 removably secured between the central portion and the rail portions, and the rail wear portions 23 and 24 integral with the central portion. For convenience in understanding the structure, the hard metal central portion is shown outlined by a heavy line.

10 The central portion is provided with the downwardly extending flanges 25 and 26 which rest on the laterally extending base flanges of the rail portions 11, 12 and 14, 15, as clearly shown in Figures 2 to 7 inclusive, 70
 15 Thus, the laterally extending securing bolts act firmly to clamp the central portion between the rail portions on the opposite sides thereof. The part 16 of the central portion of the frog is also provided with the downwardly extending flanges 27 which rest on the base flanges of the rails 10 and 13. At 75
 20 28 and 29 are shown spacing blocks positioned between the rail 13 and wing rail 12 and between the rail 10 and wing rail 15, respectively. A spacing block 30 is also provided between the rails 11 and 14 beyond the end of the hard metal central portion of the frog.

As previously explained, the point 18 and 80 the rail wear portions 21 and 22 on the opposite sides thereof are replaceable. The structure and mounting of the point 18 will first be described. The central portion of the frog is provided in the region of the point 18 with a downwardly projecting portion 31 (Figs. 5 and 6). The portion 31 is cut away to provide a substantially rectangular recess or depression in the upper face thereof, into which snugly fits the lower portion of the point 18. Thus it will be 85 seen that the part 31 forms a sort of cradle in which the point is secured by means of the transverse bolts 32 and 33.

The removable rail wear portions 21 and 90 22 are similar in construction and mounting, and only one of them, therefore, will be described in detail. Referring to Figures 3, 4, 5 and 6, it will be noted that the rail wear portion 22 is provided with the laterally and downwardly extending flange 34, the lower edge of which rests upon the laterally extending flange of the rail extension 15. By reference to Figure 11, it will be noted that the downwardly extending flange 25 of the hard central portion of the frog is offset, as indicated at 95 35, in the region of the wear member 22 in order to permit the flange 34 of the wear member to extend downwardly between the central portion and the vertical flange of the rail. Thus, the laterally extending bolts 33 and 36 of the frog act firmly to clamp the flanges of the wear sections 21 and 22 between the supporting flanges 25 of the central portion the vertical web of the side

rails. If desired, the removable point portion 18 may be provided on the under side thereof with recesses 37, 38, in order to effect a saving in weight and material.

In practice, it is found that certain portions of the frog usually wear much more rapidly than other portions. In certain cases it may happen that the point of the frog will wear out and require replacement much more often than do the side or rail wear portions. In certain instances, one of the rail wear sections will require replacement much more often than the other. The structure herein disclosed permits the various wear sections to be replaced either 75 separately or all at a time without replacing the whole frog or even the central hard portion of the frog, thus effecting a great saving in material and also in many instances a great saving in the time required 80 for replacing the worn section.

The entire frog structure shown in Figures 12 to 17 is like that shown in Figures 1 to 11, except the wear members are 85 90 replaceable as a unit instead of separately. The parts will, therefore, be indicated in Figures 12 to 17 by the same reference characters primed, as are applied to the corresponding parts in Figures 1 to 11.

The rail members 10', 11', 12', 13', 14', and 15' of Figure 12 are exactly the same as those shown in Figure 1. The spacing members 28', 29' and 30' of Figure 12 are also like those of Figure 1. Thus it will be seen that the only difference between the frog of Figure 1 and that of Figure 12 is found in the region of the replaceable members 18', 21' and 22'. By reference to Figures 13, 14, 15 and 16, it will be seen that the removable point 18' and the removable wear sections 21' and 22' of the rails are formed as an integral casting in the modification shown in Figure 12. Integral with the end portions of the manganese frog center is the saddle or supporting member 40 which supports the replaceable section and is provided with downwardly extending flanges 41, between which and the rail members the flanges 34' of the wear insert are clamped. It is believed that the form shown in Figure 12 will be readily understood without further detailed description.

The frog shown in Figure 12 is superior to that shown in Figure 1, in that the wear sections being all formed integral, they may be more firmly secured in position in the frog. The modification of Figure 12 is inferior to that of Figure 1 in that the individual wear sections, as the point or the two side members, cannot be separately replaced.

While in the present disclosure I have shown my invention applied to a rail bound frog, it is to be understood that it is equally

applicable to a frog which is not rail bound. It is also to be understood that I contemplate many modifications not herein shown or described. The invention, therefore, 5 should be limited merely by the scope of the appended claims.

Having thus described my invention, what I claim is new and desire to secure by Letters Patent of the United States is:

10 1. In combination, intersecting railroad rails, and a hard metal frog secured between said rails, said frog comprising two independently replaceable wear sections adjacent to the intersection of the wheel flange- 15 ways.

2. In combination, intersecting railroad rails, and a hard metal frog secured between said rails, said frog comprising a replaceable point and rail wear portions replaceable independently of said point on opposite sides respectively of said point and adjacent thereto.

3. In combination, intersecting railroad rails, and a hard metal frog secured between said rails, said frog comprising a replaceable point and separately replaceable rail wear portions on opposite sides respectively of said point and adjacent thereto.

4. In combination, intersecting railroad rails including wing rail portions, a hard metal frog inserted between said rails and wing portions, said frog comprising replaceable wear sections, and transverse bolts extending through aligned openings in said 35 rails, frog, and wear sections.

5. In combination, intersecting railroad rails, a hard metal frog inserted between said rails, said frog comprising removable rail wear portions adjacent to the intersection of the wheel flangeways, flanges extending downwardly from said frog into engagement with the base flanges of said rails, and flanges extending downwardly from said removable rail portions between 40 said frog flanges and the webs of said rails.

6. In combination, intersecting railroad rails, a hard metal frog inserted between said rails, said frog comprising a removable point, said frog having a recess in the upper surface thereof, the base of said point being secured within said recess.

7. In combination, intersecting railroad rails, a frog cooperating with said rails, said frog comprising a removable rail wear portion, a flange extending downwardly from said frog into engagement with one of the base flanges of said rails, and a flange extending downwardly from said removable rail portion between said frog flange and the web of said rail.

8. In combination, intersecting railroad

rails, a frog cooperating with said rails, said frog comprising a removable rail wear portion, a flange extending downwardly from said frog into engagement with the base 65 flange of one of said rails, a flange extending downwardly from said removable rail portion between said frog flange and the web of said rail, and a bolt passing through aligned openings in said frog flange, said 70 flange on the removable rail portion and the web of said rail.

9. In combination, intersecting railroad rails, a frog inserted between said rails, said frog comprising removable rail wear portions adjacent the intersection of the wheel flangeways, flanges extending downwardly from said frog into engagement with the base flanges of said rails, flanges extending downwardly from said removable rail portions into engagement with said base flanges between said frog flanges and the webs of said rails, and bolts passing through aligned openings in said frog flanges, the flanges on said removable rail portions and the webs 85 of said rails.

10. In combination, intersecting railroad rails, a frog cooperating with said rails, said frog comprising a removable point and a removable rail wear portion adjacent to the 90 intersection of the wheel flangeways, said frog having a recess in the upper surface thereof, the base of said removable point being secured within said recess, a flange on said frog extending downwardly into engagement with the base flange of one of said rails, and a flange extending downwardly from said removable wear portions between said frog flange and the web of said rail.

11. In combination, intersecting railroad rails having base flanges, a frog cooperating with said rails, and a replaceable rail wear portion having a flange extending down and bearing directly on the base flange of one 105 of said rails.

12. In combination, intersecting railroad rails, a frog inserted between said rails, said frog comprising a removable point, said frog having a recess in the upper surface 110 thereof, the base of said point being secured within said recess, and a bolt passing through said frog and through the portion of said removable point disposed within said recess.

In witness whereof, I hereunto subscribe my name this 13th day of May, 1924.

PAUL HOFFMAN.
